UNITED STATES PATENT OFFICE.

SOL EINSTEIN, WILLETS PEASLEE, AND FRED S. HAAS, OF CINCINNATI, OHIO, AS-
SIGNORS, BY MESNE ASSIGNMENTS, TO CINCINNATI GRINDERS INCORPORATED, OF
CINCINNATI, OHIO, A CORPORATION OF OHIO.

AUTOMATIC SIZE-GRINDING MACHINE.

Application filed July 29, 1925. Serial No. 46,818.

This invention relates to improvements in parting from or exceeding the spirit of the
grinding machinery and more particularly 55 to what is known as precision grinding machinery such as is normally employed for the
production of accurate cylindrical work. Machines of this type are primarily ad-
vantageous in the quantity production of similar workpieces accurate to within a frac-
tional thousandth of an inch. In their con-
struction and operation there are two points
which are of prime importance. One of these 60 points is that of accurate construction and
operation of the machine so that there will
be minimum of chatter or vibration and the
other is the provision of control mechanism
of simple but efficient character which will 65 permit of reduction to a minimum of the
time lost in gauging the size of the work or
re-setting the machine for different work-
pieces. It is the purpose of the present invention to provide a machine which is an im-
provement over the structures of the prior 70 art primarily in the matter of control of op-
eration thereof so that the various necessary
movements of the parts of the machine prior
to, during and subsequent to the grinding
operation may be accomplished in the sim-
plest and most efficient manner. A further object of the invention is the 75 provision of automatic mechanism adapted
to co-act with the workpiece whereby the
operation of the machine will be a variable
matter depending on the actual stock re-
moval rather than a so-called automatic op-
eration dependent upon the setting of cer-
tain mechanical stops or the like having 80 reference only to the movements of the ma-
chine and not to the condition of the work it-
self. A further object of the invention is the
elimination of waste time in movement of 85 the parts from inoperative to operative posi-
tion and the reverse. Further objects of the invention include 90 a simplification of the methods of operating
a machine of this type and of the mechanical
elements for accomplishing the foregoing
results substantially as hereinafter shown
and described and it will be understood that 95 any modifications may be made in the spe-
cific structural details illustrated within the
scope of the appended claims without de-

Figure 1 represents a front view of a ma-
chine embodying the invention. Figure 2 is a section view on the line 2-2
of Figure 1. Figure 3 is a section on the line 3-3 of 60
Figure 2. Figure 4 is a section on the line 4-4 of
said figure. Figure 5 is a section on the line 5-5 of
Figure 2. Figure 6 is a section on the line 6-6 of
Figure 2. Figure 7 is a fragmentary view of the feed
mechanism clutch, and Figure 8 is a diagrammatic view of the 70
electric control circuits.

In the drawings in which similar char-
acters of reference are employed to denote
corresponding parts throughout the several
views, the numeral 15 designates the bed of 75
a grinder having the longitudinally extend-
ing ways 16 for the table 17. The bed is
further formed with ways 18 for the grind-
ing wheel carriage 19. This carriage has the
bearings 20 for spindle 21 bearing the grind- 80
ing wheel 22. A feed screw 23 rotatably
engaged in nut 24 of the carriage is rotat-
ably supported in bracket 25 on the bed 15.
Rotation of this screw, therefore, serves to
impart an in and out or feeding and retract- 85
ing movement to the carriage 19. Such
movement is imparted to screw 23 through
the chain of gears 26, 27 and pinion 28, the
latter being carried by the feed-controlling
shaft 29 which extends to the front of the 90
machine. A handwheel 30 is connected
through gear box 31 with the shaft 29 for
manual actuation thereof in a conventional
manner, one form of such mechanism being
shown in co-pending application Serial 95
Number 715,860. This mechanism is so
geared down both through the gear box 31
and through the pinion and gears 28, 26 and
27 that a complete rotation of the handle
will be equivalent only to a single turn of the 100
feed screw with the result that the carriage
and grinding stone may be advanced by frac-
tions of a thousandth of an inch to most ac-
curately regulating the amount of material
removed. Necessarily this results in a very 105
slow movement of the stone carriage and

ordinarily considerable loss of time in backing off the wheel from a position where the work is completed to position to receive a new workpiece and in again bringing the stone into grinding relation to the new workpiece. As a part of this invention, therefore, certain mechanism which will be hereinafter described has been provided to obviate these prior art difficulties.

Referring first, however, to the normal operation of the machine, a workpiece 32 is clamped in position between the headstock 33 and tailstock 34, the headstock being suitably driven to rotate the work as by attached motor 35. In order that the feed may be constant, uniform and automatic, power mechanism is employed for imparting a relative feeding movement to the work and grinding member. In the present instance this feed is shown as a movement of the grinding member but it will be understood that the same result could be accomplished by a corresponding inward movement of the work, these two, broadly considered, being equivalents and therefore equally falling within the scope of the present invention. This power mechanism comprises primarily the motor 36 suitably secured to the bed 15 and having the motor pinion 37 operating through gear 38, worm 39, and wormwheel or gear 40 to drive the power or driving shaft 41. This shaft is of tubular form having integral therewith gear 42 and clutch portion 43. Gear 42 is in constant mesh with large gear 44 of the back gear unit 45 having the reduction gear 46. Rotatable within the tubular power shaft 41 is driven shaft 47 on which is slidably keyed spool 48 having clutch portion 49 and gear portion 50 respectively adapted for selective engagement with clutch face 43 or reduction gear 46. Shift lever 51 engages spool 48 and is movable by in and out sliding of a manually controllable member 52 to reciprocate member 48 from an intermediate neutral position into an interclutched direct drive from member 41 or a reduced speed drive therefrom through the gears 46 and 50.

Pivottally connected with the bed at 53 is bracket 54 having journaled therein the stub-shaft 55 having worm portion 56 meshable with the worm-gear 57 on shaft 29. A universal joint 58 co-axial with pivot 53 connects shaft 55 with shaft 47. By comparison of Figures 3 and 7 it will be understood that when bracket 54 is in raised position parts 56 and 57 will be in driving engagement while when the bracket is in depressed position as indicated in Figure 7 the worm 56 will be moved out of engagement with the wormgear and no longer operate to rotate same. The bracket is formed with a depending socketed lug 60 receiving the plunger 61 outwardly actuated by spring 62 but capable of inward yielding movement.

This plunger bears roller 63 for engagement by cam 64 on the rockshaft or spindle 65 rotatably supported by the bed. Arm 66 pivoted by linkage to arm 67 of member 68 is shiftable by rocking of handle 69 to swing the cam from vertical to horizontal position. Upward swinging movement of the cam first brings it into engagement with roller 63 of the plunger to press the bracket upward to mesh worm 56 with gear 57. This swinging movement of the bracket and thus the meshing of the parts is limited by the adjustable stopscrew 70 on the bracket contacting with a portion of the bed as indicated in Figure 3. Further movement of the cam therefore serves simply to compress spring 62. To normally maintain the cam in this position, spindle 65 is further provided with arm 71 for engagement with the solenoid 72. As a result, the parts once having been shifted into this position, they will be so held until either manually released or automatically released by interruption of the solenoid circuit de-energizing same. While so held power applied by motor 36 will serve through the chain of gearing just described to rotate feed shaft 29 at a relatively rapid rate of speed when handle 52 is drawn outwardly to throw clutch parts 43 and 49 into engagement or at a much slower or normal feeding speed when the drive is through the back gear unit 45 and gear 50. On de-energizing of the solenoid, retaining arm 71 will drop downward carrying with it cam 64 and the parts will move out of mesh as indicated in Figure 7.

The electric control circuit includes the current leads 73 and 74 from either the main source of supply as indicated or from an auxiliary source of supply. These leads normally energize the solenoid 72. In addition, however, there is provided the shunt circuit including lead 75 and 76, resistance 77 and contacts 78 and 79. One of these contacts, as 78, is held in fixed position with respect to the table 17 while the other is carried by the pivoted feeler member 80 having a contacting point 81 riding on the work. The action is such that as the size of the work is decreased the contacts 78 and 79 will approach each other and will finally close the shunt circuit 75-76. As the resistance of this circuit is less than that of the solenoid the solenoid will then become deenergized releasing arm 71 so that worm 56 will be disengaged and the inward feed of stone and work will cease. It is to be understood that the feeler mechanism and contact just described is adjustable for varying sizes of work, this mechanism being shown and claimed in detail in co-pending application Serial No. 46,816.

In a mechanism of this character it is desirable that the work and tool or grinding wheel be separated at the completion of the

grinding operation. The present invention contemplates the automatic separation of the parts a pre-determined amount at the conclusion of the said movement when the work has been brought down to proper size. Also the invention contemplates this removal being effected as respects the final position of the operative surface of the tool so that this surface may be a known distance away from a subsequent standard workpiece at the inception of the grinding operation irrespective of the amount of wear of the tool during the previous grinding. Emphasis is placed on this point as differentiated from a definite reverse movement of the carriage through reverse rotation of the handwheel as has been possible with prior-art constructions. This distinction is raised for the reason that with prior-art constructions a definite reverse rotation of the controlling means is true moves the carriage back a pre-determined amount, but as the stone wears away at each cutting the same initial position of the handle would not be satisfactory for rapid re-adjustment to grinding position with a new workpiece but calculation and allowance would have to be made for the wear which has taken place. With the present mechanism, however, as the withdrawing movement is calculated for a definite number of a thousandths of an inch from proper operating position, corresponding for example to a complete turn of the manual feed wheel, the operator knows that it is safe to make this single turn of the wheel in bringing back the grinding carriage and that such movement will neither bring the tool against the work with undue force nor will it leave the tool such a distance from the work that appreciable time will be consumed in the automatic taking up the remainder of the distance before grinding starts. In the attainment of these results there is mounted on shaft 29 the drum 181 having the clutch face 82 for co-operation with a second clutch face 83 formed on gear 57. These two clutch faces are yieldingly urged into engagement one with the other by spring 84 mounted on the shaft between drum 181 and fixed collar 85 of the shaft. This connection, therefore, provides a yieldable coupling between the parts. Secured to the drum and adapted to be wound thereon by feeding rotation of shaft 29 is the flexible connection, or chain 86 running over idler 87 and having secured to its free end the gravity actuated weight device 88. This member 88 moves in the tubular guide or dashpot 89 and has its upward movement limited by the adjustable guide bracket 90 which is slidably secured to member 89 as by the bolts 91. The adjustment of bracket 90 definitely checking the upward movement of the weight 88 also limits the winding movement of drum 181 as actuated by the yielding engagement of the parts 82 and 83. If, therefore, additional feeding rotation be applied to member 29 beyond that necessary to wind the chain or flexible connection 86 and bring parts 88 and 90 into engagement as shown in Figure 6, the additional movement will be made without rotation of the drum. The feed can thus be indefinitely continued. On the other hand when the worm 56 disengages gear 57 shaft 29 is free to reversely rotate. The force of spring 84 being sufficient to hold the drum locked to the gear 57 and the weight or equivalent pull on member 86 being sufficient the member 29 will be reversely rotated by the unwinding action of the drum moving the tool and work a definite distance apart which is entirely independent and irrespective of the indefinite feeding movement previously imparted thereto.

It has previously been mentioned that the headstock is suitably driven by motor 35 to rotate the work during grinding. At the completion of grinding operation it is desirable that this rotation be automatically stopped so that the work may be immediately removed without the necessity of the operator personally attending to the shutting off of power from the headstock. To facilitate this automatic control the flexible member or chain 86 is provided at a suitable point with the cam portion or trip lug 92 co-operating with switch lever 93 to shift this lever and break the headstock motor circuit as at 94 as the connection 86 unwinds. This breaking of the motor circuit will release the starting lever 95 at the front of the machine allowing it to move into inoperative position ready to be again shifted to start the parts when the old workpiece has been removed. The lever 93 is so positioned that the rocking movement imparted thereto by cam 92 during its winding movement will in no wise affect any of the other mechanisms of the machine.

It is to be understood that in grinding operations of the sort here involved the grinding wheel may in some instances be of sufficient width to cover the entire length of the article being operated upon while in another instance the length of the article is greater than the width of the wheel so that it is necessary to relatively reciprocate the parts during grinding. For this reason the table 17 has been shown as mounted on ways 16. In addition the table is provided with a rack 96 engaged by shift pinion 97 on spindle 98. This spindle has at its lower end the double faced gear 99 resting on the pair of beveled gears 100-101 rotatably supported on shaft 47. Each of these gears is provided with a clutch face as at 102 for selective engagement by the terminal clutch portions 103-104 of the clutch spool 105.

keyed on shaft 47 for sliding movement relative thereto. A shifter yoke 106 engages the spool and is operable through suitable linkage from the front of the machine by means of handle 107. This handle may be shifted from side to side to place the spool in either neutral position as shown in Figure 3 or to mesh with either of the bevel gears and thus impart a driving motion to 10 said gears and large gear 99 and the rack and pinion mechanism to shift the table in one direction or the other. It will be noted the speed of rotation of spindle 98 and thus of table driver depends on whether the shaft 15 47 is being directly driven or is being driven through the reduction back gear 45. Dogs 108 on the table may be employed in the customary manner to engage the lever 107 and thus automatically reverse the direction 20 of travel of the table during the grinding operation.

In the event that it is desired to manually shift or position the table irrespective of the actuation of the power mechanism, 25 spindle 109 journaled in suitable bearings 110 on the bed has at one end a pinion 111 meshing with the opposite face of the double beveled gear 99 and at its other end suitable sprocket connected by the chain 112 30 with a second sprocket operatively associated with the handwheel 113 whereby rotation of this wheel will actuate pinion 111 to shift the table in one direction or another as desired.

35 From the foregoing description taken in connection with the accompanying drawings the construction and operation of the present machine should be readily understood. It will be noted that means are provided 40 by which the position of the table longitudinally of the bed may be manually varied and that the distance between the work table and work may also be manually adjusted to initially position the parts as desired. In addition a single power mechanism may be employed which may be selectively coupled with either the table shifting or the feed mechanism or with both to positively actuate said parts.

45 It will further be observed that automatic means have been provided for checking the feeding movement when the work has been reduced to a pre-determined size and that in connection with such automatic size controlling mechanism there are additional automatic means for withdrawing the tool or grinding member from work-engaging position a definite and prescribed amount and in addition automatic means for stopping the rotation of the workpiece after the tool has been withdrawn a sufficient amount to avoid any possibility of production of flats on the workpiece.

We claim—

1. An automatic grinding machine in-

cluding a bed, a work support, and a tool carriage mounted on the bed, means for relatively shifting said parts on the bed in a direction one toward the other, work controlled means for limiting their approach, 70 and means for causing a definite separation of the tool and surface produced on the work by the tool irrespective of the previous relative advance of the parts.

2. A grinding machine including a bed, 75 a work support and a grinding wheel carriage on the bed, means for shifting the carriage toward and from the support including a source of power, manually shiftable means for variably connecting the 80 shifting mechanism with the source of power to control the rate of movement thereof, additional automatically operated mechanism for disconnecting the shifting mechanism and source of power, and work-engaging 85 means for controlling the operation of said automatic device.

3. A grinding machine including a bed, a work support carried thereby, a tool carriage movable toward and from the support, a rotatable member controlling the movement of the carriage relative to the work support, a positive actuating mechanism therefor, a drum, a yieldable coupling between the drum and shifting mechanism, 95 and means for imparting a reverse rotation to the drum to withdraw the carriage.

4. A grinding machine including a bed, a work support on the bed, a tool carriage on the bed, means for applying relative feeding and withdrawing movements to said parts, said means including a rotatable feed device, means capable of positive connection therewith for applying feed movement thereto, and additional means yieldably 100 coupled therewith for applying a limiting reverse movement to said rotatable member when the feeding force is disconnected therefrom.

5. A control device for the return movement of a grinding wheel carriage including a drum frictionally coupled with the feed mechanism of the carriage, a member-windable on the drum, means limiting the amount of winding movement thereof, 110 whereby the frictional coupling will permit a slippage of the parts if the determined winding action has occurred, and means urging the unwinding of the connection to the amount of previous winding thereof, 115 whereby said means will urge the movement of the carriage in a reverse direction when the feed mechanism is relieved of its impelling force.

6. In a grinding machine the combination 125 with the wheel carriage, of rotatable means for shifting said carriage, drive mechanism therefor, means for connecting and disconnecting said drive mechanism therewith, a drum associated with said rotating member 130

- and frictionally connected thereto for rotation therewith but capable of slippage relative thereto, means for limiting the rotation of the drum with said feed mechanism in one direction, and means for applying a definite amount of reverse rotation to the drum, the force of said reverse power being less than the frictional resistance of the coupling whereby the drum will be reversely rotated only when the rotatable feed member is free for movement therewith.
7. In a grinding machine, the combination with a movable grind stone carriage, of means for shifting the carriage to feed the stone toward the work including a rotatable member, a flexible connection windable on said rotatable member by feeding rotation thereof, and means for applying an unwinding force to said flexible member to produce a reverse or non-feeding movement of the wheel carriage.
8. In a return mechanism for a grinding wheel carriage, the combination with a rotatable carriage shifting member, of a drum yieldably coupled for rotation therewith, a flexible member windable upon the drum, adjustable means for limiting the amount of winding movement thereof whereby slippage of the coupling will compensate for additional movement of the rotatable member, and means exerting an unwinding tension against the flexible member whereby the rotatable carriage-shifting device is reversely operated in amount equal to the winding of the flexible member on the drum.
9. In mechanism of the character described, the combination with a bed, of a power shaft journaled in the bed, a transmission line including a worm gear, a bracket pivotally supported adjacent the power shaft, a worm shaft journaled in the bracket and adapted to mesh with the worm gear in the transmission line, a universal joint connecting the worm shaft and power shaft, a positive stop limiting the movement of the bracket and worm shaft in the direction of the worm gear, yielding means resiliently holding the parts against said stop, and a manually operable cam engaging said yielding means for shifting the parts into engaging position.
10. In mechanism of the character described, the combination with a bed, of a power shaft journaled in the bed, a transmission line including a worm gear, a bracket pivotally supported adjacent the power shaft, a worm shaft journaled in the bracket and adapted to mesh with the worm gear in the transmission line, a universal joint connecting the worm shaft and power shaft, a positive stop limiting the movement of the bracket and worm shaft in the direction of the worm gear, yielding means resiliently holding the parts against said stop, a manually operable cam engaging said yielding means for shifting the parts into engaging position, and an electrical retaining device for securing the parts in engaged relation.
11. In mechanism of the character described, the combination with a bed, of a power shaft journaled in the bed, a transmission line including a worm gear, a bracket pivotally supported adjacent the power shaft, a worm shaft journaled in the bracket and adapted to mesh with the worm gear in the transmission line, a universal joint connecting the worm shaft and power shaft, a positive stop limiting the movement of the bracket and worm shaft in the direction of the worm gear, yielding means resiliently holding the parts against said stop, a manually operable cam engaging said yielding means for shifting the parts into engaging position, an electrical retaining device for securing the parts in engaged relation, and a work-engaging member coupled with said electrical retaining device for causing release of the cam on prescribed reduction of the workpieces.
